UNITED STATES PATENT OFFICE.

CHARLES GARY AND JAMES E. MARSHALL, OF NEW YORK, N. Y.

TRUCK EXTENSION-LADDER.

1,035,570.

Specification of Letters Patent. Patented Aug. 13, 1912.

Application filed July 11, 1911. Serial No. 638,955.

To all whom it may concern:

Be it known that we, CHARLES GARY and JAMES E. MARSHALL, citizens of the United States, residing at New York, in the county of New York, State of New York, have invented certain new and useful Improvements in Truck Extension-Ladders; and we do hereby declare the following to be a full, clear, and exact description of the invention, such as will enable others skilled in the art to which it appertains to make and use the same.

This invention relates to truck extension ladders designed particularly for use in case of fire, but of course applicable to other uses to which it may be put.

The object of the invention resides in the provision of an improved truck extension ladder which can be easily and quickly managed, the ladder element being adapted to be extended and lowered through the instrumentality of electrically operated means.

With the above and other objects in view, the invention consists in the details of construction and in the arrangement and combination of parts to be hereinafter more fully described and particularly pointed out in the appended claim.

In describing the invention in detail, reference will be had to the accompanying drawings, wherein like characters of reference denote corresponding parts in the several views, and in which—

Figure 1 is a side elevation of a truck extension ladder constructed in accordance with the invention, certain parts thereof being shown in section and the pivoted frame in which the ladder is mounted in lowered position, Fig. 2, a plan view of what is shown in Fig. 1, Fig. 3, a side elevation of a fragment of the truck extension ladder showing the ladder frame raised and the extension ladder partly elevated; the ladder frame being broken away intermediately, Fig. 4, a front end view of the invention with certain parts removed and the ladder frame in lowered position, Fig. 5, a section on the line 5--5 of Fig. 1, Fig. 6, a view looking at the free end of the ladder frame.

Referring to the drawings, the apparatus is shown as comprising a wheeled body including front and rear trucks 10 and 11 upon which is pivotally supported by its op-

posite ends a truck frame 12. Mounted upon the forward end of the truck frame 12 is a motor 13 of the explosive type and directly in the rear of the motor 13 is mounted an electric dynamo 14, which is geared to the motor shaft 15 whereby the actuation of the motor 13 will operate the dynamo 14. Suspended from the truck frame 12 between the trucks 10 and 11 is a truss frame 16 which carries a storage battery 17 connected to be charged from the dynamo 14. The motor 13 and dynamo 14 are protected by a casing 18 upon which latter is mounted a seat 19 and a steering and controlling wheel 20. Through the instrumentality of this wheel, the driver from the seat 19 is enabled to steer the front truck 10 and control the electric current to motors 21 mounted upon the front truck, which latter are brought into play to propel the apparatus.

Mounted upon the truck frame 12 is a turn table comprising fixed and movable members 22 and 23 respectively. Rising from the member 22 is a bracket 24 and journaled in this bracket is a shaft 25 which has fixed on its terminal portion gear wheels 26 and 27 respectively. Mounted upon the member 23 is an electric motor 28, said motor being disposed adjacent the gear wheel 27 and has mounted on its shaft a gear wheel 29 in mesh with the gear wheel 27, whereby the operation of the motor 28 will rotate the shaft 25. The motor 28 is controlled from the seat 19 and actuated by a current supplied either from the dynamo 14 or the storage battery 17. Mounted on the member 23 is an air control shock absorber 30 which is operatively connected with the gear wheel 29 and serves to absorb the shock at the termination of the descent of the ladder frame. Journaled in the frame 24 is a shaft 32 upon which are mounted segmental racks 33 and 34. These racks 33 and 34 mesh respectively with gears 35 and 36 fixed upon the shaft 25. The ladder frame of the apparatus is mounted upon the segmental racks 33 and 34 and moves in unison therewith. This ladder frame comprises corner members 37 and 38, which have their inner ends secured to respective terminals of the segmental rack 34 and converge toward each other in the direction of

their outer end; and corner members 39 and 40 which have their inner ends secured to respective terminals of the segmental rack 33 and which also converge in the direction of their outer ends in a manner similar to the corner members 37 and 38. The ladder frame further includes a pair of intermediate side members 41 and 42, the former of which has its inner end secured to the central portion of the segmental rack 34 and its outer end secured to the corner member 38, while the latter has its inner end secured to the central portion of the segmental rack 33 and its outer end secured to the corner member 40. The corner members 37 and 38 are connected to the intermediate side member 41 by means of cross braces 43 which constitute ladder steps for use when the frame is raised. Likewise the corner members 39 and 40 are connected to the intermediate side member 42 by means of cross braces 44 which also constitute ladder steps for use when the ladder frame is raised. Mounted in the ladder frame formed by the corner and side members previously described inwardly of the free end of said frame is a transversely disposed frame 45 in which are journaled parallel shafts 46 and 47. The last named shaft has fixed thereon just inward of the ends of the frame 45 pinions 48 while the shaft 46 is provided at corresponding points with enlarged cylindrical portions 49. The shaft 47 is extended beyond the ends of the frame 45 and fixed on the extension thereof adjacent the intermediate side member 42 is a gear 50, while a worm wheel 51 is fixed on the extension of said shaft 47 which is adjacent the intermediate side member 41. The shaft 46 has the end thereof adjacent the intermediate side member 42 extended and fixed on said extension is a gear 52 which meshes with the gear 50 on the shaft 47. By this construction it will be apparent that upon rotation of the shaft 47 a corresponding rotation will be transmitted to the shaft 46.

Mounted in the free end of the ladder frame is a transversely disposed frame 53 in which is journaled a pair of parallel spaced shafts 54 and 55 each of which is provided with enlarged portions 56 just inward each end of the frame 53. Movable mounted between the shafts 46 and 47 and the shafts 54 and 55 is an extension ladder, corresponding faces of the sides of which latter are provided with rack teeth 57 which mesh with respective pinions 48 on the shaft 47. By this construction it will be apparent that upon the rotation of the shaft 47 in one direction the extension ladder will be moved outwardly of the ladder frame while the reverse rotation of said shaft will move the extension ladder inwardly of said frame.

It will also be apparent that during such movements of the extension ladder it will be properly guided between the shafts mounted in the frames 45 and 53.

Mounted upon the corner member 38 adjacent its inner end is a motor 59 which receives its current from either the dynamo 14 or storage battery 17. Journaled in suitable brackets upon the corner member 38 is a shaft 60 which is keyed to the shaft of the motor 59. Fixed on this shaft 60 is a worm 75 61 which operatively engages the worm wheel 51 on the shaft 47. By reason of the connections just described it will be apparent that the operation of the motor 59 will effect the rotation of the shaft 47 so as to move the extension ladder out of or into the ladder frame.

The rear truck 11 is guided by a steering mechanism 62 which is controlled from a seat 63 mounted upon the corner members 85 38 and 39. The ladder frame is locked against descent under the influence of gravity by an automatic pawl 64 mounted upon the frame 24 and engaging the gear wheel 27.

In order to elevate the ladder frame the necessary current is supplied to the motor 28 so as to effect the rotation of the shaft 25. This rotation of the shaft 25 will operate the segmental racks 33 and 34 so as to rotate the shaft 32 and lift the free end of the ladder frame. When the desired elevation of the free end of the ladder frame is had the current is cut off from the motor 28 and turned into the motor 59 so as to effect the raising of the extension ladder carried by the frame in a manner previously described. In ascending the apparatus after the ladder frame has been elevated and the extension ladder raised the braces 43 are utilized until the seat 63 is reached, the back 105 of the latter constituting a platform from which access to the extension ladder is readily had to complete the ascent. To effect the lowering of the ladder frame the extension ladder is drawn inwardly thereof in the manner previously described, and the pawl 64 disengaged from the gear 27. The motor 28 is then operated so as to rotate the shaft 25 in a direction that will result in the movement of the free end of the ladder 115 frame downward. During this downward movement of the ladder frame the current may be cut out of the motor 59 and the weight of the frame itself utilized in effecting the remainder of its descent, the shock absorber 30 cushioning the pawl thereof at the termination of its movement.

What is claimed is:

In an apparatus of the class described, the combination with a pivoted frame and means for swinging same, a motor mounted on said frame, a ladder slidably mounted in said frame having corresponding faces of

its side members provided with rack teeth, a pair of spaced gear connected shafts journaled transversely of the frame between which said ladder moves, pinions fixed on 5 one of said shafts operatively engaging the teeth on the sides of said ladder respectively, rollers fixed on the other shaft bearing against the non-toothed side of the ladder and connections between the first named 10 shaft and motor whereby the actuation of

the latter will rotate the former and effect the sliding of the ladder.

In testimony whereof, we affix our signatures, in presence of two witnesses.

CHARLES GARY.
JAMES E. MARSHALL.
